H. Tryon.

Weather Strip.

No 17,242.

Patented May 5, 1867.

UNITED STATES PATENT OFFICE.

HENRY TRYON, OF STUBEN, PENNSYLVANIA.

ARRANGEMENT OF DOOR-SILL AND DOOR-STRIP.

Specification of Letters Patent No. 17,242, dated May 5, 1857.

To all whom it may concern:

Be it known that I, HENRY TRYON, of Stuben, in the county of Crawford and State of Pennsylvania, have invented a new and useful Door - Sill and Door - Strip; and I hereby declare that the following is a full and exact description of the same, reference being had to the accompanying drawings, making part of this specification, and the letters of reference marked thereon.

10 A, Figure 1, is a door and B the frame of the same.

D, is a sill of cast iron, cast like a box and thin as stove plate of which D, Fig. 2, 15 is a top view.

C is the door strip also made of cast-iron or other suitable material. This strip is cast with a circular flange C as shown at E, and is screwed securely on the bottom of 20 the door and so adjusted and to operate something like the blade of a pair of shears in connection with the cast iron sill.

When the door is closed the door strip, E,

removes all the snow, ice, and dirt from the sill, D, the ends of the circular flange E, are 25 brought to an edge, so that when the door closes any snow or mud that may collect between the end of the door strip E, and the door jamb H, will pass into the circular flange C. There also may be a groove in 30 the bottom of the door jamb which will prevent the snow or mud from collecting in the corners of the door casing.

What I claim as my invention and desire to secure by Letters Patent of the United 35 States is—

The construction of my door strip as shown at C, in connection with the sill, constructed as described, or any other construction substantially the same and which will 40 produce the same result.

HENRY TRYON.
